(57) **CLAIM**

The ornamental design for a jug, as shown and described.

DESCRIPTION

FIG. 1 is a perspective view of a jug showing the new design;

FIG. 2 is a front elevation view of the jug of FIG. 1;

FIG. 3 is a left side elevation view of the jug shown in FIG. 1, the right side view being a mirror image thereof;

FIG. 4 is a rear elevation view of the jug shown in FIG. 1;

FIG. 5 is a top plan view of the jug shown in FIG. 1; and,

FIG. 6 is a bottom plan view of the jug shown in FIG. 1.

The broken lines in the figures illustrate unclaimed environment and form no part of the claimed design.

1 Claim, 6 Drawing Sheets(56)
